FIG. 1.

FIG. 2.

FIG. 3.

FIG. 4.

Inventor:

William H. Van Meer,

Witness:

Bred C. Roscher,

By

F. G. Fischer,

Attorney.

UNITED STATES PATENT OFFICE.

WILLIAM H. VAN MEER, OF LONGTON, KANSAS.

TRUSS.

Application filed August 6, 1923. Serial No. 655,868.

My invention relates to improvements in rupture appliances and has for its object the cure of either single or double hernia. One feature of the invention resides in one or 5 more hollow segmental spherical pads adapted to fit over the affected parts, and owing to the shape of said pads and the manner in which they are supported are reliably held in place irrespective of the position 10 which the wearer may assume.

Another feature resides in the supporting means for the pad or pads, said supporting means being adjustable to fit different size persons.

15 Other features will hereinafter appear, and in order that the invention may be fully understood, reference will now be had to the accompanying drawing, in which:—

Fig. 1 shows the appliance in position 20 upon the body and arranged for double hernia.

Fig. 2 is an enlarged sectional view of the pad and an arm to which it is adjustably connected.

25 Fig. 3 is a plan view of the pad.

Fig. 4 is a detail of one of the arms.

In carrying out the invention, I employ a belt 2 consisting, preferably, of a spring metal band 4 provided at its ends with straps 30, one of which has a buckle 8, so that the belt 2 may be adjusted to persons of different sizes. The band 4 is covered with suitable cushioning material as leather 10 to render it comfortable to the body.

35 12 designates a pad constituting an important feature of the invention. Said pad 12 is of suitable material such as hard rubber and is of hollow segmental spherical formation as shown by Figs. 2 and 3. The pad 40 12 has a centrally-disposed slot 14, and exterior grooves 16, any of which are adapted to receive lugs 18 at the slotted end 20 of a metallic arm 22. The foregoing arrangement permits the pad 12 to be adjustably 45 connected to the arm 22, so that said pad 12 may be arranged at different angles to fit the curvature of the abdomen. After being properly adjusted the pad 12 is secured to the arm 22 by a screw 24 and a nut 26, which latter has an elongated head 28. The opposite 50 end of the arm 22 is pivotally secured to the

metal band 4 of the belt 2 by a screw 29 and a nut 30, the end of the arm being provided with radial corrugations 31 for engagement with similar corrugations on the band 4 to 55 reliably hold the arm 22 from turning on the screw 29 after the nut 30 has been tightened. The pad 12 is further held in position upon the wearer by straps 32 fixed at their upper ends to the metallic band 4 of 60 the belt 2 and provided at their lower ends with slots 33, any of which are adapted to pass over the nut 26 and be secured by turning said nut a quarter of a revolution, so that the projecting ends of the head 28 will 65 overlap the sides of the engaged slot.

In case of double hernia two pads 12 and two arms 22 are employed, as shown by Fig. 1. When two pads 12 are employed as shown, a strap 34 is used to coact with the 70 arms 22 and straps 30 in holding the pads 12 in spaced relation to each other. In case of single hernia one pad 12 and one arm 22 are dispensed with and both straps are connected to the remaining pad 12 by the nut 26. 75

A truss made according to the above explained invention, will invariably remain in its proper position when the patient is walking, sitting, or stooping over and will not exert annoying pressure at any particular 80 place.

While I have shown and described the preferred form of the invention, I reserve the right to make such changes as properly fall within the spirit and scope of the claims. 85

Having thus described my invention, what I claim and desire to secure by Letters Patent, is:—

1. In a rupture appliance, a hollow segmental spherical pad having a central slot 90 and exterior grooves spaced at opposite sides of said slot, an arm having a longitudinal slot adjacent to one end and lugs spaced at opposite sides of said slot for entering the grooves in the pad and permit the same to be 95 adjusted to different angles to fit the abdomen, a headed screw extending through the slots in the pad and said arm, a nut engaging said screw and having an elongated head to overlap the slotted portion of the 100 arm to hold the same and the pad in assembled position, and means coacting with

- said arm in holding the pad in position on the person.
2. In a rupture appliance, a pair of hollow pads, a belt, a pair of upwardly diverging arms pivotally connected to the belt and having corrugations engaging complementary corrugations on said belt, a pair of upwardly diverging straps pivotally connected to the belt, a transverse strap, and an element extending through each pad and adjustably connecting thereto the adjacent ends of said arms and said straps.
- 5
- In testimony whereof I affix my signature.

WILLIAM H. VAN MEER.
